UNITED STATES PATENT OFFICE.

AUGUST ROSENTHAL, OF WEST ALLIS, WISCONSIN.

DISCHARGE-SPOUT.

1,030,016.

Specification of Letters Patent. Patented June 18, 1912.

Application filed September 29, 1910. Serial No. 584,407.

To all whom it may concern:

Be it known that I, AUGUST ROSENTHAL, a citizen of the United States, residing in West Allis, in the county of Milwaukee and 5 State of Wisconsin, have invented new and useful Improvements in Discharge-Spouts, of which the following is a description, reference being had to the accompanying drawings, which are a part of this specification.

10 This invention relates to improvements in discharge spouts for corn husking and shredding machines and relates more particularly to spouts or discharge tubes provided with flexible elbows and discharge ends whereby the discharge tube may be inclined in any direction desired.

The principal object of this invention is 20 to provide a discharge tube which may be bent to any convenient angle or height desired to discharge material therefrom.

A further object of this invention is to 25 provide a discharge tube or spout with a flexible portion which is strong and durable and which contains but a minimum number of parts and is inexpensive to manufacture.

30 A further object of the invention is to provide a flexible elbow or discharge end for a stacker tube which is formed of sheet metal bent into spiral formation and so riveted together as to permit the structure to be bent at different angles.

With the above, and other objects in view 35 the invention consists of the discharge tube and its parts and combinations as set forth in the claims, and all equivalents thereof.

In the accompanying drawing in which 40 the same reference characters indicate the same parts in all of the views: Figure 1 is a side view of the discharge end of a discharge tube provided with the improved flexible portion; Fig. 2 is a vertical sectional view thereof; Fig. 3 is a transverse sectional view thereof; Fig. 4 is a side view 45 of a portion of the sheet metal of which the flexible part is formed before it is bent into spiral formation; and Fig. 5 is a side view of a lower portion of a stacker tube provided with the improved flexible portion in the 50 form of an elbow.

Referring to the drawing the numeral 8 indicates the upper portion of a discharge spout or tube of ordinary construction to

which is connected the improved flexible discharge end 9. The flexible end is formed 55 of a strip of sheet metal 10 wound spirally with one of the side edges thereof overlapping the edge of the adjacent convolution, thus forming a flexible tube. In order to preserve the same diameter of the tube 60 throughout its length the flexible portion of the strip of metal is of curved form and when wound the outer overlapped edge of the metal is slightly larger in diameter than the inner edge to compensate for the thickness 65 of the material and to permit the flexing of the tube. In some cases it may be desirable to crimp the edges of the metal to further increase the differences between the diameters of the inner and the outer edges of 70 the convolutions. The convolutions of the tube are held in spaced relation with each other by means of rivets 11 which pivotally connect said convolutions together. These rivets are equi-distantly spaced and divide 75 the tube circumferentially into five parts and extend longitudinally in five lines and connect portions of alternate adjacent convolutions together. The rivets of the lines are staggered circumferentially with relation to each other and each complete convolution has only three rivets extending therethrough in order not to bind the convolutions into a rigid structure. The portion of the metal strip below each pivotal connection 80 on the inside is cut away to increase the flexibility of the joint and to save metal. A band 12 is connected to the outer end of the flexible tube to give a finished appearance thereto.

In Fig. 5 the flexible joint is shown connected to the lower end of the discharge tube 8 and also to the outer end of the inner portion of the tube 13 to form a flexible elbow 14 which is constructed in the same 95 manner as the flexible discharge end of the tube. The convolutions of the joint are wound and overlap in the direction of the line of travel of material within the tube so that the inner edges of the convolutions 100 will not obstruct the passage of material through the tube.

From the foregoing description it will be seen that a discharge tube provided with the improved flexible joint is adopted to be 105 bent at any angle and also in any direction

desired and that the joint is strong and durable and does not require outside supporting or reinforcing means.

What I claim as my invention is:

- 5 1. A discharge spout, comprising a flexible tube formed of a spirally wound strip of material with overlapping portions, and means pivotally connecting the overlapping portions together at a plurality of 10 points circumferentially, said means pivotally connecting the overlapping portions together being alternately staggered circumferentially with relation to each other.
- 15 2. A discharge spout, comprising a flexible tube formed of a spirally wound strip of metal with overlapping portions, the outer edge of each convolution being of larger diameter than the inner edge, and rivets extending through the overlapping portions at a plurality of points circumferentially to pivotally connect said portions to-

gether, said rivets being staggered circumferentially with relation to each other and spaced equi-distant spirally from each other.

- 25 3. A discharge spout, comprising a flexible tube formed of a spirally wound strip of metal with overlapping portions, and longitudinal lines of rivets extending through the overlapping portions at a plurality of 30 points circumferentially to pivotally connect said portions together, said rivets being staggered with relation to each other and spaced equi-distant spirally from each other.

35 In testimony whereof I affix my signature in presence of two witnesses.

AUGUST ROSENTHAL.
